INVENTOR
WILLIAM JAMES MARRISON

BY
Henry S. Blackmore
ATTORNEY

UNITED STATES PATENT OFFICE.

WILLIAM JAMES MORRISON, OF TORONTO, ONTARIO, CANADA.

FIREARM.

1,359,726.

Specification of Letters Patent. Patented Nov. 23, 1920.

Application filed March 22, 1918. Serial No. 223,905.

To all whom it may concern:

Be it known that I, WILLIAM JAMES MORRISON, a subject of the King of Great Britain, residing at Toronto, Province of Ontario, Dominion of Canada, have invented certain new and useful Improvements in Firearms, of which the following is a specification.

This invention relates more particularly to an automatic, or gas operated, firearm of the repeating type, such as disclosed in my companion application filed December 7, 1917, bearing Serial Number 205,971.

The object of the present invention is to furnish a firearm of the above type with a stock that may be easily and quickly converted into a polyped gun support or rest for the barrel of the gun, to facilitate supporting and accurately aiming the gun.

A further object of the invention is the provision of novel means for detachably connecting the stock parts to a pistol handle section of the firearm.

The above and other objects are attained by a mechanical construction that will be hereinafter specifically described and then claimed, reference being directed to the drawings which illustrate the invention in one of its applications and adaptations, in which:

Figure 1 is a side elevation of a portion of the firearm on the line 1—1 Fig. 6, partly in section;

Fig. 1^A is a longitudinal sectional view of the barrel portion of the firearm;

Fig. 2 is an enlarged detail view, partly in plan and partly in section of the barrel portion of the firearm;

Fig. 3 is a view similar to Fig. 1 showing the position of parts for placing a cartridge in a barrel;

Fig. 4 is a horizontal sectional view of the breech portion of the firearm, partly in plan;

Fig. 5 is a similar view showing a cartridge ejecting and holding mechanism; and

Fig. 6 is a cross sectional view of a portion of the firearm on the line 6—6 Figs. 1 and 2 showing the portion of the stock in position as a tripod or rest.

Similar numerals of reference indicate corresponding parts in the several views.

In the drawings 50 and 51 denote portions of a stock having the inner ends thereof pivotally connected or hinged, as at 52 and the portions 50 and 51 articulated by

toggle members 68 that will retain the portions in tripod or rest form, as shown in Fig. 6.

The portion 51 has an apertured lug 61 adapted to engage the pistol handle 62 of the breech portion 12 of the firearm. The pistol handle 62 has an opening and recess 58 providing clearance for a locking pin 57, said pin having a head 59 in the recess of 65 the pistol handle engaged by a spring 60, which holds the locking pin normally retracted. The lower end of the locking pin is adapted to engage in the apertured lug 61 and is forced therein by a stud 56 on a lever 53, pivoted, as at 54, in a recess of the stock portion 50. A spring 55 in the stock portion 50 holds the outer end of the lever flush with the surface of the stock portion 50, and the pistol handle 62 is cut away to provide 75 clearance for the end of the lever, so that the stud 56 may engage the locking pin 57 and force said pin into the apertured lug 61 to lock the stock portions 50 and 51 in engagement with the pistol handle. 80

The lower portion of the fore stock 17 has a curved locking pin 65 provided with a shoulder 67 and spring 66, and with the stock portions 50 and 51 in polyped gun support or rest formation, as shown in Fig. 6, the 85 curved locking pin 65 is adapted to engage in the apertured lug 61 and be retained therein by the stud 56 of the lever 53 carried by the stock portion 50. It is therefore apparent that the gun may rest upon the polyped support or rest afforded by the stock portions 50 and 51 and may be properly sighted by tilting the gun through the medium of a pistol handle 62. This novel gun stock permits of a shoulder firearm, being readily 90 converted into a polyped supported gun. 95

Considering the remaining portions of the firearm, which have been described in detail in my companion application, bearing Serial No. 205,971, filed December 7, 1917, 15 denotes a trigger which when pulled upon releases the hammer 14 and this hammer strikes a firing pin 68 which in turn strikes the cap of the cartridge in the chamber of the barrel 11, exploding the cartridge and 100 driving the bullet out of the barrel. An enormous pressure is instantly generated by the gases of the explosion and these gases under pressure will enter the port 32 of the barrel 11, pass through a port 31 and impinge against a piston head 28 in the cylinder 27. The head 33 of the cylinder has 105

check valve parts 35 and 36 in connection with the port 34. When the piston head 28 is moved backwardly the spring 37 is placed under compression and the bridle 18 is shifted. This bridle in turn unlocks a breech block 13 by forcing the locking bar 44 in an upward direction from the pivot 46, thereby locking the firing pin. When this motion takes place the breech block is carried back to the full extent of the breech frame, carrying the empty cartridge case which is ejected by the mechanism shown in Fig. 5. The same movement of the breech block re-cocks the hammer 14, and a buffer spring 39 checks the movement of the whole mechanism, which quickly returns to loaded position with a new cartridge from the magazine 16 in position. At the same time, the piston head 28 is forced forward and the air which has entered the cylinder through the port 34, following the creation of a vacuum behind the piston head is forced through the port 32 and exhausts through the muzzle of the gun, producing a suction which scavenges the barrel 11 and replaces the hot gases with cool air drawn through the chamber. The loading action is the reverse of the firing action, except that a new cartridge is obtained from the magazine. As these cartridges are used the final cartridge is left in the chamber, but not fired until the empty magazine has been replaced by a full one. A conventional form of magazine block has been shown and after the magazine is in position, the gun is ready for firing.

Other reference numerals of the drawing designate similar parts referred to in my companion application Serial Number 205,971.

Although the detailed description of the arm is described and claimed in my co-pending application Serial Number 205,971 and is shown and described in the present application in connection with the same, it is not intended to be limited thereby as the present invention may be combined with a gun or firearm of any description to which it may be applicable and adaptable, and which may be provided with the pin actuated securing member in such a manner as to co-act and coöperate with and between the firearm and the present invention to provide a means for attachably and detachably securing the combination.

Having now described my invention what I claim is:—

1. A firearm having a detachable stock, comprising a movable polyped portion adapted for supporting the barrel portion

of the firearm, a locking pin carried by a portion of the firearm, means carried by the stock to coöperate with the locking pin for detachably securing the stock to the firearm, and a spring actuated lever to hold the pin and locking means in operative position.

2. In a firearm, a detachable bifurcated stock carrying a spring-actuated lever, a barrel portion carrying a locking pin, and means for bringing the lever to the pin in coacting locking relation for attaching them together.

3. In a firearm, having a pistol handle, a detachable stock provided with a spring-actuated lever carried thereby, and a barrel portion carrying a locking pin, thus providing a locking means to secure the barrel and the stock in operative position and adapted to attach the stock intermediate of the ends of the firearm.

4. In a firearm having a pistol handle, a detachable, bifurcated stock, a barrel member, locking means disposed at the pistol handle and adapted for holding the stock in engagement with the barrel, and a locking means comprising a locking pin and a co-acting and coöperating spring-actuated lever, said locking means communicating with the stock and the barrel members in such a manner as to co-act and coöperate in detachably locking the barrel to the stock.

5. The combination of a firearm, locking pins carried by portions thereof, a bifurcated stock adapted for attachment to the locking pin portions of the firearm, and means carried by the stock adapted to actuate the locking pins to hold the stock in engagement with portions of the firearm.

6. The combination with a firearm having a pistol handle of a locking pin carried by the pistol handle, a swinging bifurcated stock detachably held by said locking pin and adapted as a polyped rest member when attached, and spring actuated means carried by the stock adapted for connecting the converted stock to a barrel portion of the firearm as a rest member therefor.

7. The combination of a firearm, locking pins carried by portions thereof, a bifurcated stock adapted for attachment to the locking pin portions of the firearm, and spring means carried by the stock adapted to actuate the locking pins to hold the stock in engagement with portions of the firearm.

In testimony whereof, I affix my signature in the presence of two witnesses.

WILLIAM JAMES MORRISON. [L. S.]
